CLAIM

The ornamental design for a mug with a hockey puck bottle opener, as shown and described.

DESCRIPTION

FIG. 1 is a bottom perspective view of a mug with a hockey puck bottle opener showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the mug with a puck bottle opener that form no part of the claimed design.

1 Claim, 6 Drawing Sheets
